3 Claims. (Cl. 315—10)

This invention relates to imaging devices for the infrared portion of the light spectrum. In particular this invention relates to a novel photoconductive target for use in a new improved infrared pickup tube.

In the past there have been various materials suggested for use as targets for infrared pickup tubes. Generally, it has been necessary that the materials used for targets in these devices have a resistivity of at least 10^{11} ohm cm. in order that the target have the ability to store electrical charges for the $\frac{1}{30}$ second frame time of the scanning beam. For line storage type of operation, materials having a resistivity of approximately 10^9 ohm cms. are usable. A further requirement of the materials used in infrared pickup devices is that these materials be highly sensitive at wavelengths that extend well into the infrared portion of the light spectrum. Some materials are known that are sensitive to infrared wavelengths of the desired frequency. However, these materials do not have the required resistivity for pickup tube operation. Other known materials have the proper resistivity but are not sensitive to the desired infrared wavelengths.

It has been found that some materials have resistivities that increase as the material is cooled. Therefore, certain materials which have a response that extends into the infrared range of the spectrum are usable when the target is cooled to a low temperature. In the pickup tubes used for infrared purposes prior to this invention, cooling of the target has been a considerable problem. One complicating factor is that the target receives heat by radiation from the thermionic cathode of the electron gun used in the tube.

It is therefore an object of this invention to provide a new and improved infrared pickup device.

It is another object of this invention to provide a new and novel target electrode for an infrared pickup device.

It is a further object of this invention to provide a new and improved infrared pickup tube including therein a new and novel target electrode.

These and other objects are accomplished in accordance with this invention by providing a new and improved photoconductive target that is sensitive to infrared radiations, and a novel tube structure is provided for cooling the target. Generally, the tube comprises an electron gun, arranged in an off-axis arm of an evacuated envelope, for producing an electron beam. The electron beam from the gun is deflected around a bend in the elongated envelope to enter the main portion thereof where it is scanned over the target structure. A return beam from the target structure is deflected into a second off-axis arm of the envelope to strike an electron multiplier and produce output signals therefrom. With this arrangement of tube structures, the target of the tube is shielded from the gun cathode so that heat radiated therefrom is prevented from striking the target. The improved target includes a sensitive infrared photoconductor of the single crystal or polycrystalline type. The target material is suitably activated to provide a spectral sensitivity corresponding to energies associated with the desired infrared wave lengths.

The above and other objects will be better understood by reference to the following description when read in

2

conjunction with the accompanying single sheet of drawings wherein:

FIGURE 1 is a fragmentary sectional view of a pickup tube in accordance with this invention;

FIGURE 2 is an enlarged fragmentary sectional view of the target shown in FIGURE 1.

Referring specifically now to FIGURE 1, there is shown a fragmentary sectional view of a pickup tube 10 in accordance with this invention. The tube 10 comprises an envelope 12 having a main, or body, portion 14 and two off-axis arms 16 and 17, which arms have axes offset from the axis of the body portion. As shown, the envelope 12 also includes a third arm 18, the purpose of which will be explained hereinafter. Within the arm 16 there is provided an electron gun 20 that includes a conventional cathode 21, control electrode 26 and one or more accelerating electrodes 22 for providing an electron beam 23. Surrounding the end of electron gun 20 is a first hollow tubular accelerating electrode 28. Adjacent to the other end of accelerating electrode 28 is second accelerating electrode 28' for accelerating the beam 23 down the arm 16 into the body portion 14 of envelope 12. The electron gun 20 may be of any conventional type and further description thereof is not deemed necessary. Surrounding the arm 16 is a focus coil 24 for providing a magnet field parallel to the axis of envelope portion 16 and for focusing the electron beam 23 as it traverses the arm 16. Surrounding the focus coil 24 is an alignment coil 25 for providing a field transverse to the axis of envelope portion 16 and for correcting any misalignment of the electron beam 23. Both the focus coil 24 and the alignment coil 25 may be of any well known type and therefore it is not believed to be necessary to describe them in detail.

In the junction area of the arms and body portion of envelope 12 there is provided a decelerating field provided by electrode 31 which is connected to a conductive coating 33 such as tin oxide. Electrode 31 is operated at a potential that is negative to accelerating electrode 28' to decelerate the beam as it enters the junction region of the envelope, as well as to aid in maintaining beam focus. The electron beam 23 is bent into alignment with the body portion 14 of envelope 12 by means of a magnetic field produced by an electromagnet producing field lines perpendicular to the path of the electron beam of the magnet 27. Only one pole of the magnet is shown for simplicity of illustration with the other pole piece being arranged on the opposite side of envelope 12. When the electron beam 23 passes through the magnetic field produced by the electromagnet 27, the path of the electrons in the beam is bent to enter the body portion 14 of envelope 12. The current in the electromagnet 27 is adjusted to give optimum deflection, or bending, of the beam into the body portion of envelope 12. The deflection field used here is normally a few gauss in magnitude.

Within the body portion 14 of the envelope 12 there is provided a hollow tubular focusing electrode 34, which forms an electron lens with the conductive coating 33, and through which the electron beam travels in a relatively field free space. Adjacent to the target end of the tubular electrode 34 is a hollow decelerating electrode 36 that is closed on one end by an apertured mesh screen 38. The mesh screen 38 is permeable to the electron beam 23 and acts as a decelerator electrode in certain types of operation.

Surrounding the body portion 14 of envelope 12 is a deflecting yoke 29 which, in turn, is surrounded by a main focusing coil 30 providing a magnetic field parallel to the axis of envelope portion 14. When the electron beam 23 from gun 20 is deflected into the body portion 14 of

the envelope 12, it enters the body portion 14 substantially on the axis thereof, and substantially follows the magnetic lines of force of the focus coil 30 which focuses the beam 23 onto a target 32 in the other end of the envelope. Potentials are applied to the deflection yoke 29 to deflect the beam over the surface of target 32, in a well known manner.

The target 32 may comprise layer 42 of photoconductive material, and has a conductive backing, or signal plate 40 formed of a very thin layer of evaporated gold. The conductive coating 40 should be thick enough to be electrically conductive, yet thin enough to be transparent to infrared radiations. The thickness of the gold coating 40 is between 200 to 400 angstrom units in thickness.

In accordance with this invention, the photoconductive material 42 is either a single crystal, or a polycrystalline material into which impurity materials have been introduced to provide photoconductive sensitivities in the desired range of the spectrum and the proper resistivity for use in a pickup tube. The crystalline target material may be doped, i.e., it may have impurities introduced into the material by any of the recognized procedures.

A target material in accordance with this invention that has produced excellent results is one obtained from a single crystal of silicon that is doubly doped with gold and indium. A crystal of this type is formed by adding sufficient material to a crucible, not shown, in which the materials are melted, to provide gold atoms of a concentration which is within the approximate range of one half the number of indium atoms to a substantially equal number of gold atoms as indium atoms in the resulting silicon crystal. With the presently available silicon, the total amount of impurity atoms in the final crystal is approximately 10^{15} to 10^{16} impurities per cubic centimeter of the crystal.

Another target material in accordance with an embodiment of this invention is a crystal of doubly doped silicon wherein the doping materials are boron and gold. These materials are added in amounts to provide a concentration of gold that is within the approximate range of one half the number of boron atoms to substantially equal concentration of gold and boron atoms in the final crystal of silicon.

A still further target material in accordance with this invention is a crystal of germanium that is doped with atoms of arsenic and gold. The amount of gold atoms added is within the approximate range of one half the number of atoms of arsenic to a substantially equal concentration of gold and arsenic atoms in the final crystal.

Specific examples of the proportions of the materials in the embodiments of the target 32 that were described above are as follows. (1) To 100 grams of silicon add 10 grams of gold and 0.14 gram of indium, (2) To 100 grams of silicon add 1 microgram of boron and 2.5 grams of gold, (3) To 100 grams of germanium add 450 milligrams of gold, to this mixture add 500 grams of germanium doped with arsenic at a concentration of approximately 15 micrograms of arsenic per cubic centimeter of germanium.

The target 32 may be varied in thickness from about two to thirty mils. The most sensitive targets made to date were under ten mils in total thickness. Diameters to about one inch have been used.

Any of the targets described above may be treated with a non-reflecting material to reduce the radiation lost by reflection at the radiation incident side of the target. An example of such a material is a mixture of 32 grams of sodium hydroxide in 100 cubic centimeters of water. The solution is placed on the radiation incident side of target 32 for five minutes at 75°C. Then hydrofluoric acid is applied to the same side for five minutes at room temperature. This material substantially reduces radiation lost by reflection, and also is electrically conductive so that it may be used as the signal plate 40.

When desired, a very thin film of evaporated gold on

the radiation incident side of target 32 may be used as a signal plate 40, as was described above.

Surrounding the target 32 is a target cooling cell that comprises a hollow target support member 50 on which the target 32 is supported as shown. The target 32 is held in the hollow annular member 50 by a pair of screws 51 that press an annular member 53 against the target. The target is pressed against a relatively soft indium washer 55 which is seated in the hollow support member 50. The hollow elongated support member 50, which may be of a material such as silver plated copper, encloses an annular space 56 through which a coolant, e.g. liquid nitrogen, may be circulated to cool the target 32. The space 56 communicates with the exterior of the cooling cell by means of a re-entrant portion 54. The temperature of the target 32 may be measured by means of a thermocouple 61 that contacts an edge of target 32. With liquid nitrogen used as a coolant, targets have been operated at temperatures that were about 2 degrees above that of the liquid nitrogen, i.e. 77° K.

Adjacent to the other end of the elongated target support 50 is supported a thin, e.g. $\frac{1}{16}$ of an inch, infrared transmitting window 52 that may be of a material such as sapphire. The window 52 may be removably positioned on the cooling cell by means of screws 57 that press the window against a gasket 65 on the cooling cell. In the area around both the window 52 and the target 32 the envelope is evacuated since, the target cooling cell is sealed to the body portion 14 of envelope 12 by means of a rubber gasket 60.

The reason for the target cooling cell is that it has been found that certain materials operate with greater sensitivity, and more useful resistivities, when these materials are cooled to particular temperatures. It should be understood that the target 32 may be made of many known materials which have infrared sensitivity when cooled to a predetermined temperature.

With cooling below liquid nitrogen temperature, even longer wavelength response can be obtained with the targets described above. At liquid helium temperature one could use silicon doped only with indium at the desired wavelengths while still maintaining a resistivity that is sufficiently high for pickup tube operation. In this example the wavelength response corresponding to the indium impurities would extend to about 8 microns. Other impurities, e.g. gallium, having even longer wavelength response, could be used at liquid helium temperature.

During operation, a coolant is also circulated around the walls of the body portion 14 by being inserted into the inlet 63 which permits the coolant to flow around the body portion 14 of envelope 11, and between the focusing coil 30 and the deflection yoke 29. An example of a coolant for this purpose is air that has been cooled in a liquid nitrogen heat exchanger, not shown.

When the electron beam 23 is deflected into the body portion of envelope 14, the heat from the cathode is not deflected and thus impinges on the walls of body portion 14. Thus, the heat from the cathode is cooled by the coolant inserted into inlet 63 so that no heat from the cathode 21 reaches the target.

Enclosed within the arm 17 of envelope 12 are three hollow tubular accelerator electrodes 43, 44 and 46 for accelerating a return electron beam 45 into a conventional electron multiplier 47 from which output signals are obtained during tube operation. The return beam 45 is deflected into arm 17 by means of the electro magnet 27, due to the fact that it is traversing the magnetic fields from the magnet in the opposite direction from that of scanning beam 23, and is focused onto the electron multiplier by a focusing coil 58.

When potentials are applied to the tube 10, such as those shown as an example in FIGURE 1, the beam 23 scans the target 32 at energies such that more primary electrons land on the target than secondary electrons are driven from the target. Thus, when no radiation is directed onto

the target 32, the scanned surface of the photoconductor 42 is driven in a negative direction to a reference potential that is substantially the same as that of cathode 21. When infrared radiations are directed onto the photoconductor 42, it becomes conductive in the elemental areas that are struck by the radiation to establish a charge, with respect to the reference potential, on the scanned surface of the photoconductor 42. When the beam 23 re-scans the charged areas, it replaces the reference potential. This replacement of the reference potential produces a variation in the return beam 45 which corresponds to the amount of radiation on the target. The variation of the return beam 45 acts as an output signal from tube 10, when this variation is multiplied by the multiplier 47.

Arm 18 may be used for (1) inserting images onto the scanned side of target 32, or (2) a target may be tested by inserting another electron gun, not shown, in the arm to determine how a target is affected by the heat from a straight through gun as compared to the off-axis gun 20. Likewise, thermal radiation characteristics of certain electron guns may be evaluated in this manner.

This invention has described novel target structures as well as a novel tube structure. The targets are extremely sensitive to infrared radiation, as an example, they have shown good response beyond 3.7 microns. The novel tube structure provides an excellent means for cooling the target during operation.

What is claimed is:

1. An infrared pickup tube comprising an envelope including an elongated body portion having an axis and a pair of off-axis arms on one end of said body portion, said arms having axes which intersect the axis of the body portion at an angle, an infrared sensitive photoconductive target in the other end of said body portion, an electron gun positioned inside and adjacent the outer end of one of said arms at a point sufficiently remote from the intersection of the body portion and the arm that a straight line contained within the tube cannot interconnect the electron gun and the target because of the offset of the arm axis, said electron gun being positioned to emit an electron beam substantially along the axis of the arm containing the gun, an electron multiplier in the other of said arms, and means adjacent to the intersection of said body portion and said arms for bending the emitted electron beam from the axis of the arm containing the electron gun to the axis of the body portion for impingement on said target and for bending an electron beam reflected from said target along the axis of the body portion to the axis of the arm having the electron multiplier.

2. An infrared pickup tube comprising an envelope including an elongated body portion having an axis and a pair of off-axis arms on one end of said body portion, said arms having axes which intersect the axis of the body portion at an angle, an infrared sensitive photoconductive target in the other end of said body portion, said target comprising a transparent conductor, a crystal of silicon on said conductor and having substantially the same number of atoms of impurities of boron as the number of atoms of impurities of gold in said silicon, an electron gun positioned inside and adjacent the outer end of one of said arms at a point where a straight line contained within the tube cannot interconnect the electron gun and the target, said electron gun being positioned to emit an electron beam substantially along the axis of the arm

containing the gun, an electron multiplier in the other of said arms, magnetic means adjacent the intersection of said body and said arms for bending the emitted electron beam from the axis of the arm containing the electron gun along the axis of the body portion for impingement on said target and for bending a reflected electron beam from the target along the axis of the body portion to the axis of the arm having the electron multiplier, and means for cooling said target.

3. An infrared pickup tube comprising an envelope having an elongated body portion having an axis and a pair of off-axis arms at one end of said body portion, said arms having axes which intersect the axis of the body portion at an angle, a target electrode adjacent to the other end of said body portion, said target electrode including a crystal of silicon having gold and indium impurities therein, said impurities being present at a concentration of approximately 10^{15} to 10^{16} impurity atoms per cubic centimeter of said crystal, said target also including a transparent conductive coating on one surface of said crystal, an infrared window at said other end of said body portion and spaced from said target electrode, means for cooling said target electrode and the space between said target and said window, means for cooling the walls of said body portion, an electron gun positioned inside and adjacent the outer end of one of said arms at a point where a straight line contained within said envelope cannot interconnect the electron gun and the target, said electron gun being further positioned to emit an electron beam substantially along the axis of the arm containing the gun, means adjacent to the intersection of said body portion and said arms for bending the emitted electron beam from the axis of the arm containing the electron gun along the axis of the body portion for impingement on said target and for bending a reflected electron beam from the target along the axis of the body portion to the axis of the arm having the electron multiplier, and means for scanning said beam over said crystal.
